United States Patent Office

Des. 182,737
Patented May 6, 1958

182,737

HANDBAG OR SIMILAR ARTICLE

Gladys Murray, New York, N. Y., assignor to Bernard Cahn Co., Inc., New York, N. Y.

Application December 12, 1957, Serial No. 48,883

Term of patent 7 years

(Cl. D87—3)

I claim:

The ornamental design for a handbag or similar article, substantially as shown.
